UNITED STATES PATENT OFFICE.

FREDERICK W. HOCHSTETTER, OF DAYTON, OHIO, ASSIGNOR OF ONE-HALF TO W. I. OHMER, OF DAYTON, OHIO.

PROCESS AND APPARATUS FOR SENSITIZING PHOTOGRAPHIC FILM AND PAPER.

1,403,779.

Specification of Letters Patent. Patented Jan. 17, 1922.

Application filed November 13, 1919. Serial No. 337,824.

To all whom it may concern:

Be it known that I, FREDERICK W. HOCHSTETTER, a citizen of the United States, residing at Dayton, in the county of Montgomery and State of Ohio, have invented certain new and useful Improvements in Processes and Apparatus for Sensitizing Photographic Film and Paper, of which the following is a specification, reference being had therein to the accompanying drawing.

The object of my invention is to sensitize photographic film and paper, or any other mediums which may be desired to be sensitized, so that the resulting product will be thoroughly uniform and will not be subjected to the variations to which it is subjected today.

Another important object of my invention is to provide a method and process by which the manufacture of this sensitized material may be greatly expedited and be made much more economically than it is today.

By my process and method, the operation is continuous, with practically no handling of the material, with the consequent great advantage in not only the economy of cost, but in the perfection of the resulting product.

Specifically, it is my object to only handle the paper, or other medium treated with the emulsion, once. It is another object to cut the medium to be used into suitable sizes before it is sensitized so that this cutting can be done in the full daylight and not in the dark after it has been sensitized. It is not only difficult to cut it in the dark, or what amounts to dark, but it is also injurious to the sensitized surface.

It is my object to so handle the paper that the present disadvantages of having the sensitized paper touched by human fingers, or having it exposed to different lights or different temperatures, will be obviated.

This, of course, results in having paper of uniform sensitiveness because of the gradual change in temperature, and by my method, even depth of emulsion, resulting in a sensitized material of uniform speed.

It is another object of my invention to economize in the extent of the apparatus necessary for performing these operations, and to provide an apparatus which may be readily controlled in its operation and in its temperature.

Figure 1 illustrates a mechanism for executing my process.

Figure 2 is a top-plan view of Figure 1.

Figure 3 is a side elevation of another form, illustrating the method of conveying the strips of sensitized material one above the other, permitting of the use of a relatively narrow apparatus.

1 is the roll of paper or film, which usually is furnished in a broad sheet. 2, 2 are cutting discs, which cut the broad strip into narrower strips. These narrower strips are parted one from another by the divided roller 3. The individual strips are passed around the guide roller 4, provided with a series of flanges 5, to keep the strips separate and guided in the proper direction. 6 is also an additional guide roller. 7 is a roller turning in the sensitizing emulsion 8 in the trough 9 maintained at a proper temperature by well known means. This emulsion roller 7 carries the emulsion in contact with the strips 1, 1, from the supply 8. These strips are carried beneath the roller 10 and upwards over the guide roller 11 into a cooling chamber A, where the temperature is at 50° F. The refrigeration apparatus is designated generally by 12. The strips are passed over the rollers 13, 13, as guide rollers. The strips then pass into the chamber B, where the temperature is maintained at from 70 to 80° F. and is known as the drying compartment. This compartment has its temperature and air conditions maintained by the conditioning apparatus generally designated by 14. The material passes through this chamber B over the rolls 15, 15, which serve as guides. Then the various strips pass into a second drying chamber C, where the temperature is from 80 to 90° F. This chamber C has its air likewise conditioned. The material passes through chamber C into chamber D, where the temperature is maintained at from 95 to 110° F. This is a seasoning compartment. The air in this compartment is likewise conditioned.

The material then passes out between the rollers 16, 16, which serve to draw it through the various compartments, and it then hangs in a slack or slight loop 17 before it passes to a perforating machine 18 in order to give it sufficient latitude of movement during the intervals of perforation. There is another slack 17a before it passes between the rolls 110.

19, 19. This slack or slight loop 17^a provides for any manipulation or adjustment necessary during the course of the microscopic inspection to which the film is subjected. The film is moved by an intermittent movement across the field of vision of the inspector and having a slight loop prevents any strain being put upon the emulsified medium. 20, 20 are guide rolls. 21 is 5 the inspector's microscope illuminated with a lamp 22. 23 is the intermittent movement mechanism which allows sufficient time for inspection before moving the emulsified medium forward. 24 is another loop before 10 it passes over the roller 25 to the supply reel 26. The loop 24 is of use when a portion of the medium is found faulty so that it may be cut out of the strip and the strip joined together again before it goes on to be wound 15 upon the reel 26.

It will be readily understood that I have described the course of treatment given to a single strip and that Figure 1 merely illustrates the mechanism for such treatment. 25 There will be a plurality of other strips as mentioned heretofore, not illustrated in this view, which would lie behind it in the illustration, all of which would have similar treatment and would progress to their ultimate destination simultaneously. The case 30 of the single strip is taken as typical of the treatment given to all.

27 is the tank of emulsion which is kept at a temperature of 85° F. This tank is supplied with the filter 28 which is supplied by 35 29, which empties into a graduate 30. The supply from the graduate to the tank 9 is controlled by the pet cock 31.

To summarize, my process is as follows: 40 I cut the broad strip into a series of narrow strips prior to sensitizing such strips. I then sensitizes the strips at a temperature of 85° F. The sensitized strips are passed, after having their treatment of sensitizing 45 emulsion, to a refrigeration compartment at a temperature of 50° F. This sets the emulsion. The strips are all traveling together at the same rate parallel to one another, which effects a great economy in the 50 size of the apparatus and its capacity. The strips then pass into a drying room where the temperature is raised from 70 to 80° F. From this drying room B they are conveyed 55 into drying room C, where the temperature is increased again from 80 to 90° F. And from the drying room D, temperature 95 to 110° F., the strips are conveyed into the conditioning room and thence they are perforated, if they are not already perforated, 60 inspected and wound for storage or use.

It will be observed that the emulsified strips are untouched by human hands during the course of manufacture, which is a distinct step in advance over the present 65 state of the art. It will be noted that the

size of the apparatus can be very materially reduced over what is now utilized in the commercial sensitizing of media. The capacity of the apparatus is multiplied very largely by the multiplicity of strips which 70 can be treated at one time in one apparatus.

In Figure 2 the same reference numerals refer to the same parts as in Figure 1. In Figure 3, this is also true. Figure 3 illustrates the various strips of material superimposed above one another. No special explanation is necessary, as the drawing itself is self-explanatory and clearly illustrates the method employed.

The conditioning of the various compartments is obtained by feeding thereto air which has been conditioned in a manner well known in industrial plants. The air is freed from all foreign matter and is delivered at a prescribed temperature and the 80 usual humidity free from foreign matter. In each of the conditioning compartments air of the proper temperature, of uniform humidity from time to time in each compartment and free from foreign matter surrounds the medium passing through the compartment. The amount of humidity in any one compartment is suitably controlled in a well-known manner.

Having thus fully described my invention, what I claim as new and desire to secure by Letters Patent, is:

1. In a process of sensitizing a medium, sensitizing said medium, reducing the temperature of said medium, elevating the temperature of said medium, elevating the temperature of said medium again, elevating the temperature of said medium a third time, and restoring the temperature of said medium to normal.

2. In a process of sensitizing a medium, sensitizing said medium at 85° F., cooling it in a temperature of 50° F., initially drying it in a temperature of 70 to 80° F., additional drying in a temperature of from 80 to 90° F., seasoning it in a temperature from 95 to 110° F., and restoring it to normal temperature of the surrounding air in finished condition.

3. In a process of sensitizing a medium, sensitizing said medium at 85° F., cooling it in a temperature of 50° F., initially drying it in a temperature of 70 to 80° F., additional drying in a temperature of from 80 to 90° F., seasoning it in a temperature from 95 to 110° F., resorting it to normal temperature of the surrounding air in finished condition, and inspecting.

4. In a process of sensitizing a medium, dividing a strip of the medium into a plurality of strips, sensitizing said strips at 85° F. temperature, passing said strips into a temperature of 50° F., passing said strips into a temperature from 70 to 80° F., passing said strips into a temperature of 80 to 90° F.

F., passing said strips into a temperature of 95 to 110° F., and reducing the temperature of said strips to that of the surrounding air.

5. In a process of sensitizing a medium, dividing a strip of the medium into a plurality of strips, sensitizing said strips at 85° F. temperature, passing said strips into a temperature of 50° F., passing said strips into a temperature from 70 to 80° F., passing said strips into a temperature of 80 to 90° F., passing said strips into a temperature of 95 to 110° F., reducing the temperature of said strips to that of the surrounding air, and perforating said strips.

10 6. In a process of sensitizing a medium, dividing a strip of the medium into a plurality of strips, sensitizing said strips at 85° F. temperature, passing said strips into a temperature of 50° F., passing said strips into a temperature from 70 to 80° F., passing said strips into a temperature of 80 to 90° F., passing said strips into a temperature of 95 to 110° F., reducing the temperature of said strips to that of the surrounding air, and inspecting said strips.

15 7. In a process of sensitizing a medium, dividing a strip of the medium into a plurality of strips, sensitizing said strips at 85° F. temperature, passing said strips into a temperature of 50° F., passing said strips into a temperature from 70 to 80° F., passing said strips into a temperature of 80 to 90° F., passing said strips into a temperature of 95 to 110° F., reducing the temperature of said strips to that of the surrounding air, perforating said strips, and inspecting said strips.

20 8. In a process of sensitizing a medium, dividing a strip of the medium into a plurality of strips, sensitizing said strips at 85° F. temperature, passing said strips into a temperature of 50° F., passing said strips into a temperature from 70 to 80° F., passing said strips into a temperature of 80 to 90° F., passing said strips into a temperature of 95 to 110° F., reducing the temperature of said strips to that of the surrounding air, perforating said strips, inspecting said strips, and winding said strips.

25 9. In combination, in an apparatus for treating a medium comprising in succession, a sensitizing apparatus, a refrigeration chamber, a drying chamber, a seasoning chamber, and means in each of said chambers for the passing therethrough of the medium, whereby a medium is treated for photographic purposes.

30 10. In combination, in an apparatus for treating a medium comprising in succession

a supply roll support, cutting disks, sensitizing apparatus, a refrigerator, a drier, a seasoning chamber, and means in each of the refrigerator driers and seasoning units for passing the medium therethrough, whereby a medium is treated for photographic purposes.

35 11. In combination, in an apparatus for treating a medium comprising in succession a supply support, cutting disks, dividing disks, sensitizing apparatus, a refrigerator, a drier, a seasoning chamber, and means in each of the refrigerator driers and seasoning units for passing the medium therethrough, whereby a medium is treated for photographic purposes.

40 12. In combination, in an apparatus for treating a medium, comprising in succession cutting disks, sensitizing apparatus, a refrigerator, a drier and a seasoner, and means in said refrigerator, drier and seasoner for passing a strip of a medium therethrough horizontally whereby a medium is treated for photographic purposes.

45 13. In combination, in an apparatus for treating a medium comprising in succession, cutting disks, sensitizing apparatus, a refrigerator, a drier and a seasoner, and means for passing strips of a medium therethrough whereby a medium is treated for photographic purposes.

50 14. In combination, in an apparatus for treating a medium comprising in succession, cutting disks, sensitizing apparatus, a refrigerator, a drier and a seasoner, and means for passing strips of a medium therethrough one above another, whereby a medium is treated for photographic purposes.

55 15. In combination, in an apparatus for treating a medium comprising in succession cutting disks, sensitizing apparatus, a refrigerator, a drier and a seasoner, and means for passing a series of strips of a medium therethrough, one series of strips having its component members travel parallel to one another and another series superimposed one above another.

60 16. In a process of sensitizing a medium, sensitizing said medium, reducing the temperature of said medium, elevating the temperature of said medium, elevating the temperature of said medium again, elevating the temperature of said medium a third time, and restoring the temperature of said medium to normal, all of said steps in difference of temperature being gradual changes, whereby uniformity of product is secured.

In testimony whereof, I affix my signature.
FREDERICK W. HOCHSTETTER.
